UNITED STATES PATENT OFFICE.

VICTOR E. CLARK, OF GRAND RAPIDS, MICHIGAN, ASSIGNOR TO THE VICTOR BROOM COMPANY, OF DETROIT, MICHIGAN, A CORPORATION OF MICHIGAN.

BROOM.

1,015,263.

Specification of Letters Patent.

Patented Jan. 16, 1912.

Application filed January 30, 1911. Serial No. 605,557.

To all whom it may concern:

Be it known that I, VICTOR E. CLARK, a citizen of the United States of America, residing at Grand Rapids, in the county of Kent and State of Michigan, have invented certain new and useful Improvements in Brooms; and I do hereby declare the following to be a full, clear, and exact description of the invention, such as will enable others skilled in the art to which it appertains to make and use the same.

My invention relates to improvements in brooms, and its object is to provide a broom so constructed that the brush part of the same may be readily removed when the same becomes worn and a new one inserted, and to provide the same with various new and useful features hereinafter more fully described and particularly pointed out in the claims, reference being had to the accompanying drawings in which:—

Figure 1 is a perspective of a device embodying my invention; Fig. 2 a central vertical section of the same; and Fig. 3 a horizontal section on the line 3—3 of Fig. 2.

Like numbers refer to like parts in all of the figures.

1 represents the brush portion of a broom of substantially the same shape and material as are usually made of broom corn, except that the upper end terminates in a substantially horizontal plane and the material is secured only by means of sewing through the same as at 2 in the manner usual in making brooms. Above where the brush is secured in this way the ends of the broom corn or other material is unsecured and extends upward a sufficient distance to be secured in a sheet metal clamp consisting of opposing members 3 spaced apart a suitable distance and at the top provided with inwardly projecting concave members 4 to oppositely engage the sides of the handle 7. The upper part of each member is preferably in the form of a semi-circular arch and the interior of each arch is severed in a semi-circle and turned inward at right angles and provided with an opening 9 to receive the tapered and screw-threaded end 8 of the handle 7. The bottom of each member is curved inward as at 6 to form a stiffening member and also to more securely clamp the broom therebetween. At the lower corners of each member are end extensions 10 turned inward at right angles and slidably over-

lapping each other. These clamp members are preferably made of stamped sheet metal and are drawn toward each other close above the upper end of the brush by the tapered and screw threaded end of the handle extending through the openings in the overlapped inwardly turned portions 5 whereby they are drawn toward each other by the tapered screw thread. This tapered end of the handle is also forced downward 65 and into the upper portion of the brush by rotating the same. The inwardly projecting members 4 at the top serve to hold the upper part of the clamp members spaced apart and traverse the handle as the same is forced 70 downward by the screw. The device thus securely holds the brush in place for use and when the same is worn, or otherwise useless, by turning the handle to run the screw out the brush can be released and a new one 75 inserted and securely clamped therein by turning the handle in to place. Should the brush become loosened in the clamp by use, it is readily tightened by turning the handle in a little farther, the device thus serving to 80 detachably and securely hold the brush in place and being obviously cheap and effective for the purpose.

What I claim is:—

1. A broom, comprising a brush, a clamp 85 embracing the brush, inwardly projecting and slidably overlapping perforated members on the clamp close to the brush, inwardly projecting concave members at the top of the clamp, and a handle oppositely engaged 90 by the concave members and having a tapered and screw threaded end extending through the perforated members and into the brush.

2. A broom, comprising a handle having a 95 tapered and screw threaded end, a brush, sheet metal clamps oppositely engaging the brush and extending above the same, said clamps having at the upper end inwardly projecting members to engage opposite sides 100 of the handle and also having inwardly projecting and overlapping members near the middle provided with openings to receive the end of the handle and having their lower ends adapted to embrace and hold the brush. 105

3. A broom, comprising a handle having a tapered and screw threaded end, a clamp comprising sheet metal members each having an arched upper part provided with inwardly turned portions at the top to engage 110

the handle and also having semi-circular portions turned inward and slidably overlapping and provided with openings to receive the said end of the handle and having its lower edge turned inward to engage and hold a brush.

4. A broom, comprising a brush formed of broom corn and secured by sewing transversely intermediate its ends, a clamp adapted to embrace the upper part of the brush and having overlapping, inwardly projecting members close above the upper end of the brush and overlapping members at each

edge of the brush and also having inwardly projecting members at the top to engage the handle, and a handle having a tapered and screw threaded end inserted in the clamp and extending into the upper end of the brush. 15

In testimony whereof I affix my signature in presence of two witnesses.

VICTOR E. CLARK.
